United States Patent Office.

JEROME C. DIETRICH AND CHARLES I. HUMPHREY, OF ROCHESTER; NEW YORK.

Letters Patent No. 92,022, dated June 29, 1869.

IMPROVED PLASTERING-TROWEL.

The Schedule referred to in these Letters Patent and making part of the same.

To all whom it may concern:

Be it known that we, JEROME C. DIETRICH and CHARLES I. HUMPHREY, of the city of Rochester, in the county of Monroe, and State of New York, have invented certain new and useful Improvements in Masons' Plastering-Trowels; and we do hereby declare that the following is a full and exact description thereof, reference being had to the accompanying drawings, making part of this specification.

Our invention relates to the construction of the arm or standard which connects the handle with the trowel-blade, and is applicable to both spreading and finishing-trowels.

Heretofore this arm has usually been a straight bar, which some have widened out so as to protect the hand from the mortar, and to increase the bearing surface, which presses against the forefinger of the hand, while operating with it.

In using a trowel, the great strain comes upon the hand, which is required to grasp the round handle with sufficient force to steadily hold the trowel-blade at the proper inclination or position relative to the wall. The power and fulcrum being on opposite sides of the handle, the force exerted is applied at a great mechanical disadvantage.

By permitting the standard to press against the forefinger of the hand, the fulcrum is in a measure transferred to that point, which is so much nearer the resistance, or trowel-blade, as to enable the instrument to be used with greater ease.

The object of our invention is to so construct this standard as to enable it to be grasped between the thumb and forefinger, and easily held without bruising or straining the hand, as would be the case were the standard constructed in the ordinary manner.

The invention consists in constructing the front side of the standard so as to form a depression or seat for the thumb, as will hereafter be fully explained.

In the drawings above referred to—

Figure I represents a side elevation of my improved trowel, with the handle shown in section.

Figure II is a perspective view.

Figure III is a front elevation.

Like letters of reference designate like parts in each of the figures.

A is the trowel-blade;

B, the wooden handle; and

C, the arm or standard connecting the two, which is cast or otherwise formed, with a shank, d, for fitting in the handle, and a corresponding one, d', for attachment to the trowel-blade. The latter will vary in construction according as it is designed for a spreading or dressing-trowel.

e is the channel or recess formed across the stand, at the rear, for receiving the forefinger.

f f are the extended wings of the same, which curve toward the front, as shown; and

g g are depressions or seats for the thumb, formed in the front side, the wings f serving as guards to retain the thumb in place.

From what has been before stated, the operation of our improvements is obvious; the handle being grasped by the right hand, the forefinger will naturally fit in the channel e, which so distributes the pressure against it, as to prevent the wearing or bruising of the finger, while the thumb, which is placed over the end of the handle, in the depression g, is equally well protected by the corresponding construction thereof.

These depressions e g, not only thus protect the thumb and finger from injury, but also form seats that retain them in place, and form the fulcrum of the trowel while it is being used.

What we claim as our invention, and desire to secure by Letters Patent, is—

The standard C, formed with depressions g, and curved wings f, with or without the recess e, as herein shown and described.

JEROME C. DIETRICH.
CHAS. I. HUMPHREY.
